Primary Examiner — Stacia Cadmus(74) *Attorney, Agent, or Firm* — Ralph E Smith(57) **CLAIM**

The ornamental design for an automobile wheel, as shown and described.

DESCRIPTION

FIG. 1 is a right side perspective view of an automobile wheel showing our new design;

FIG. 2 is a left side perspective view thereof; and,

FIG. 3 is a front view.

It will be understood that the broken lines shown in the drawings illustrate portions of the automobile wheel that form no part of claimed design.
